FRICTION CAN TOP

Fred A. Durrant, Kansas City, Mo., assignor to
 Tayton Company, Kansas City, Mo., a corporation of Missouri

Application February 11, 1935, Serial No. 6,027

2 Claims. (Cl. 220—23)

This invention relates to a novel and useful device for retaining the descriptive literature, preferably a folder, readily accessible on the cover or top of a container.

5 An object of this invention is the provision of simple and efficient means for holding the package descriptive folder in the cover or top of a can.

Another object of the invention is the construction of a simple and efficient means for attaching 10 a package folder to a can.

A still further object of the invention is the provision of means in a tin friction top for holding the descriptive literature in the top and partly exposed to view, and readily accessible to the user of 15 the contents of a can upon which the top is mounted, for full perusal.

With the foregoing and other objects in view, my invention comprises certain novel constructions, combinations and arrangements of parts as 20 will be hereinafter fully described, illustrated in the accompanying drawing, and more particularly pointed out in the appended claims.

In the drawing:

Figure 1 is a top plan view of a device constructed in accordance with the present invention, while

Figure 2 is a sectional view taken on line 2—2, Fig. 1.

Figure 3 is an enlarged fragmentary sectional view similar to Figure 2.

It is desirable to have the descriptive literature not placed in the container with its contents, for reasons hereinafter given, and, therefore, I have preferably arranged on the outside of the container or can novel means for efficiently retaining the package folder, as I now shall proceed to specifically describe. Consequently, in this preferred embodiment of my invention, I place in the depressed portion of the metal cover or top 1 a

40 flexible or yieldable disc 2, which disc is provided with a centrally arranged window or sight-opening 3. This disc 2 is frictionally held in top 1 by reason of its edge snugly fitting and clamping the inner wall of the depressed portion of the top.

45 The descriptive literature or folder 4 is positioned under the sight-opening 3, in the chamber between the bottom of the depressed portion and the yieldable, friction disc 2. This folder 4, by reason of its folds, has a springy action on the

50 friction disc to increase the friction of the disc against the inner wall of the top to hold the disc more securely in the top. This friction action is greatly augmented by a portion of the printed means or literature, extending into the sight 55 opening and exerting pressure on the edges of said opening as clearly shown at 5, Fig. 3. This is a novel construction which increases the efficiency of my device in retaining the folder or printed

matter in a position whereby the prospective purchaser, or owner of the can can quickly consider the entire literature without disturbing the contents of the can. In other words, the printed folder can be easily placed in position, or removed 5 for full inspection, at the will of the operator. Further, the friction disc 2 greatly protects the printed matter from dust and dirt.

The combination which I have described is essential in the production of a device for the purpose specified. Therefore, by this combination of elements, the attaching of the package folder in the can top eliminates the "messiness" of the package folder being put into the can with the powder, such as a malted milk preparation, or the 15 like. My invention allows the upper one-fourth of the package folder, showing the headline, to be read through the sight-opening 3 of the disc 2 when the can is picked up by the prospective purchaser. Another advantage of my device resides 20 in the fact that the disc 2 may bear advertising, and thereby become a factor in furthering the sale of the product. It may also be desirable to work out a number of tricks appealing to children, and expose them in a suitable manner on the 25 disc showing how the disc can be used in performing the tricks.

What I claim is:

1. In a device of the class described, the combination of a can top provided with a depressed 30 portion, a disc provided with an open sight-opening down in said depressed portion, said disc outwardly-bowed throughout, and a folder of descriptive matter and having a springy action under said disc and pressing against same adjacent 35 said open sight-opening, whereby said folder permits the operator's finger to enter the sight-opening and grip its edge for quick and easy removal of said disc.

2. In a device of the class described, the combination of a can top provided with a depressed portion, a flexible friction disc provided with a central open sight-opening, said disc being entirely within said depressed portion and also being evenly bowed outwardly throughout its entire width and pressing at its entire edge against the inner wall of said depressed portion, and a folder of a descriptive nature and having a springy action under said disc and also provided with a portion extending into said sight-opening 50 and exerting pressure against the edge of said sight-opening, whereby said folder may be compressed at the sight-opening by the operator's finger entering and gripping the edge of said sight-opening for easily removing the disc, substantially as shown and described.

FRED A. DURRANT.
